UNITED STATES PATENT OFFICE

118,837

DESIGN FOR A VELOCIPEDe FRONT FORK

John Gordon Rideout, Cleveland, Ohio, assignor
to Junior Toy Corporation, Hammond, Ind.

Application June 8, 1939, Serial No. 85,398

Term of patent 14 years

To all whom it may concern:

Be it known that I, John Gordon Rideout, a citizen of the United States, residing at Cleveland, in the county of Cuyahoga and State of Ohio, have invented a new, original, and ornamental Design for a Velocipede Front Fork, of which the following is a specification, reference being had to the accompanying drawing, forming part thereof.

Fig. 1 is a perspective view of a velocipede front fork showing my new design.

Fig. 2 is a front elevational view thereof.

Fig. 3 is a side elevational view of the velocipede front fork.

I claim:

The ornamental design for a velocipede front fork, substantially as shown.

JOHN GORDON RIDEOUT.
